(57) **CLAIM**

The ornamental design for a lighting bezel of an agricultural vehicle, substantially as shown and described.

DESCRIPTION

FIG. 1 is a perspective view of a lighting bezel of an agricultural vehicle, in which the phantom lines illustrate portions of a lighting system of the agricultural vehicle;

FIG. 2 is a top view of the lighting bezel, in which the phantom lines illustrate portions of the lighting system of the agricultural vehicle;

FIG. 3 is a bottom view of the lighting bezel, in which the phantom lines illustrate portions of the lighting system of the agricultural vehicle;

FIG. 4 is a left side elevation view of the lighting bezel, in which the phantom lines illustrate portions of the lighting system of the agricultural vehicle;

FIG. 5 is a right side elevation view of the lighting bezel, in which the phantom lines illustrate portions of the lighting system of the agricultural vehicle;

FIG. 6 is a front view of the lighting bezel, in which the phantom lines illustrate portions of the lighting system of the agricultural vehicle; and,

FIG. 7 is a back view of the lighting bezel, in which the phantom lines illustrate portions of the lighting system of the agricultural vehicle.
